RESILIENT FLOOR CONSTRUCTION

Leo E. Kuhlman, Detroit, Mich.

Application March 8, 1956, Serial No. 570,314

2 Claims. (Cl. 20—6)

This invention relates to building construction and has particular reference to resilient, or active floors, such as disclosed in my co-pending application Serial No. 221,647, filed Apr. 18, 1951, now Patent 2,743,487 of which this application may be considered a continuation in part.

It is an object of this invention to generally improve resilient floors, such as disclosed in my co-pending application, and to provide such a floor, with improved means to positively control the vertical and lateral movement of the floor, under all operating conditions.

Another object of the invention is to provide positive means for preventing the floor from jumping upwardly under the reflex action of the springs.

A further object of the invention is to provide improved means for directly carrying and evenly distributing any imposed load on the finished floor, over the widest area, upon the downward flexing of the springs.

A still further object of the invention is to provide means for limiting the movement and absorbing the shock, caused by any extreme lateral movement of the finished floor under the influence of the springs, when in use.

Another object of the invention is to provide means for anchoring the finished floor in place and preventing the floor from buckling or warping.

Another object of the invention is to provide improved stops for the downward flexing of the springs, which stops also serve as stiffeners for the finished floor.

Another object of the invention is to retard the transmission and reflection of sound by the floor.

Another object of the invention is to provide under-floor ventilation for retarding rot and deterioration.

Another object of the invention is to provide shoe means around the perimeter of the floor, which are secured to the walls and overlie the floor, and serve as means to prevent dust and dirt from collecting in the space between the walls and floor, and also serve to help limit the reflex movement of the springs supporting the floor.

The foregoing and other objects and advantages of the invention will become more apparent as the description proceeds, reference being made from time to time to the accompanying drawing forming part of the within disclosure, in which drawing:

Fig. 1 is a fragmentary plan view, with parts in section, of a structure embodying the invention, with the sub-floor and finished floor removed.

Fig. 2 is an enlarged fragmentary, perspective view, with parts in section, and parts broken away and illustrating the upper left hand corner of the structure shown in Fig. 1.

Fig. 3 is a section taken substantially on the line 3—3 of Fig. 1.

Fig. 4 is a section taken substantially on the line 4—4 of Fig. 1.

Fig. 5 is a section taken substantially on the line 5—5 of Fig. 1.

Fig. 6 is a section taken substantially on the line 6—6 of Fig. 1.

Fig. 7 is a section taken substantially on the line 7—7 of Fig. 1.

Referring now more particularly to the drawing, it will be understood that in the embodiment herein disclosed, the reference character 11 indicates the side walls 10 of a building structure, having a concrete under-floor 12, upon which rests a plurality of rectangular steel plates 13, which are positioned to receive the curved portions 14 (Figs. 4 and 7) of the leaf springs 15, which leaf springs 15 are bolted, as at 16, to the longitudinal members 17, which serve as joists for supporting the sub-floor 18 and the finished floor 19. A layer of slaters felt 20, and a layer of deadening felt 21, are preferably interposed between the finished floor 19 and sub-floor 18, as shown in Figures 2 to 7, to assist in cushioning the sound. It will be noted that the leaf springs 15 normally lie perpendicular to the axes of the longitudinal members 17, except along the perimeter of the floor, where the springs 15A are positioned beneath the members 17A, in parallel relation. In order to provide adequate length for the longitudinal members 17, it is necessary to provide splicing blocks 22 (Fig. 1).

Also positioned beneath the sub-floor 18, as shown in Figs. 2 and 7, I provide stiffening members 23. These stiffening members 23 are deeper than the longitudinal members 17, with which they are parallel, and serve as direct load carrying members, when the floor is moved downwardly, a predetermined distance upon the flexing of the leaf springs 15. The members 23 also serve as limiting stops for the downward movement of the sub-floor 30 and finished floor, upon the flexing of the springs 15, and evenly distribute the weight of the finished floor and sub-floor over a substantially wide area. The stop and load members 23 are spaced at suitable intervals beneath the sub-floor.

In order to help control the lateral movement of the sub-floor 18 and finished floor 19, under the influence of the springs 15, and prevent warping and buckling of the floor, and to limit the upward movement of the sub-floor 40 18 and finished floor 19, upon the reflexing of the springs 15, I provide a novel means for anchoring the sub-floor and finished floor as shown in Figs. 1 and 6. Before the concrete comprising the under-floor 12 completely sets, I embed therein, at spaced intervals, a plurality of bolts 24. The bolts 24 are set in the concrete under-floor 12, so that their free ends may be received in suitable bores 25, formed in the longitudinal members 17, whereby the longitudinal members 17 are free to slide on the bolts 24 a limited distance. As shown in Figs. 6, the sub-floor 50 18 is recessed, as at 26, to accommodate the nut 27 of the bolt and a large washer 28, which is positioned beneath the nut. The bolts 24, the nuts 27 and the washers 28, in cooperation with the upper faces of the longitudinal members 17, limit the upward movement of the sub-floor 18 and finished floor 19 upon the reflex action of the springs 15. On the other hand, the bolt heads 27 coming in contact with the finished floor 19, assist in limiting the downward movement of the sub-floor 18 and finished floor 19, upon the flexing of the springs 15. This 60 action is in addition to the limiting action provided by the stop and stiffening members 23 as hereinabove described.

In order to absorb the shock and to help limit the lateral movement of the sub-floor 18 and finished floor 70 19, I provide lateral springs 15B which are secured to the sides of the members 17A and ride against the wall 12. In addition to using the lateral springs 15B, I also con-

template the use of rubber bumpers between these parts, as disclosed in the co-pending application indicated above.

In order to further limit the upward movement of the finished floor 19, upon the reflexing of the springs 15, I provide an angular metal shoe 29 (Figs. 2, 3 and 5), one leg of which is bolted to the side wall 12, and the other leg of which over-rides the outer periphery of the sub-floor 18 and the finished floor 19. These shoes 29 are positioned so that the finished floor is in easy contact with the shoes, when the springs 15 are in their normal position, as shown in Figs. 3 and 5.

It is believed that the operation of the device is obvious from the foregoing description.

From the foregoing, it will be seen that I have provided an active, resilient floor construction, in which the movement of the floor in all directions is carefully controlled.

Having described my invention what I claim and desire to secure by Letters Patent is:

1. In a building construction, including fixed walls, a concrete under-floor, a sub-floor and a finished floor, the combination of a plurality of longitudinal members for supporting said sub-floor and finished floor, arcuate spring members secured at their centers to said longitudinal members, in spaced relation, the springs on one member being staggered with respect to the springs on an adjacent member, elongated stiffening members se- 25

cured to the underside of said sub-floor, parallel to said longitudinal members and at right angles to said springs, said stiffening members, being deeper than said longitudinal members and serving as direct floor load carrying members, when said springs have been flexed a predetermined distance.

2. The structure of claim 1, including a plurality of bolts deeply embedded in said concrete under-floor and extending upwardly to be slidably received in passageways formed in said longitudinal members, there being means on said bolts co-operating with said longitudinal members, whereby to limit the reflexing of said springs, and help limit the lateral movement of said finished floor and sub-floor.
